CHARLES E. SMITH, OF OAK LAWN, RHODE ISLAND.

MEANS FOR BOOKING METALLIC LEAF.

949,850.

Specification of Letters Patent. Patented Feb. 22, 1910.

Application filed February 18, 1909. Serial No. 478,746.

To all whom it may concern:

Be it known that I, CHARLES E. SMITH, a citizen of the United States, residing at Oak Lawn, in the county of Providence and State of Rhode Island, have invented a new and useful Improvement in Means for Booking Metallic Leaf, of which the following is a specification.

It is the object of my invention to provide gold beaters with an improved means for placing the sheets of gold leaf within the paper leaves of the book in which they are to be packed; and it consists in the employment of a suction device for removing the sheet of metallic leaf from the pad on which it is trimmed, and in the employment of a blast of air to cause the said sheet of metallic leaf to be transferred from the suction device onto the leaf of the book.

20 In the accompanying drawings:—Figure 1 represents a side view of the improved suction device for booking metallic leaf. Fig. 2 represents an axial section of the same. Fig. 3 represents an under side view showing 25 the perforated diaphragm. Fig. 4 represents a section taken in the line 4, 4, of Fig. 1. Fig. 5 represents a top view of the valve plug.

In the drawing, A represents the outer 30 casing of the suction chamber B, and C represents a thin porous or perforated diaphragm extending across the mouth of the said chamber, the said diaphragm being preferably made of a substance like gold beater's skin, or silk, and in the case of the former substance small openings a, a, are provided for the entrance of air through the diaphragm into the suction chamber B. The diaphragm may be secured to the casing A 35 of the chamber by means of a circumscribing groove k, and a tightly drawn cord L, or otherwise. The tube D extends upward from the center of the casing A, and divides into the two tubes E and F, of which E is a 40 suction tube and F a blowing tube. A flexible air-exhausting tube G is attached to the outer end of the suction tube E, and a flexible air-conducting tube H is attached to the outer end of the blowing tube F. The passages between the tubes E and F and the tube D are opened and closed as desired, by 45 means of the spring-actuated sliding valve I, the spring h of which holds the valve nor-

50 mally open for the passage of air through the blowing tube as shown in Fig. 2. Now whenever the diaphragm C is placed upon an outspread sheet of gold or other metallic leaf lying upon the cutting pad of the gold beater, and the sliding valve I is pressed inward by bearing against the projecting end 55 b of the valve plug, so that the passage between the blowing tube F and the tube D will be closed, and the passage between the suction tube E and the tube D opened, then the sheet of metal leaf will be sucked away 60 from the underlying pad upon which it has been deposited and cut, and carried up against the side of the diaphragm, and there held by the force of suction. The suction device may now be carried to the book in 65 which the sheets of metallic leaf are to be packed, and then, by allowing the resiliency of the spring to carry the valve I outward, so as to open the passage from the blowing tube F into the tube D and close the passage 70 from the suction tube E, the sheet of metallic leaf will be gently blown from the diaphragm C and be deposited on the leaf of the book.

The valve openings c and d are made in 75 the cylindrical valve plug e as shown in Fig. 5 and the valve is prevented from turning on its axis, by means of the pin f of the plug and the slot g of the hollow arm K, the actuating spring h being placed over the stem i 80 of the plug the pin j forming a suitable stop for the movement of the valve.

I claim as my invention:

In a portable device for sucking up and 85 depositing metallic leaf, the combination of a suction chamber casing provided at its under side with a diaphragm permeable by air, means for drawing air inwardly through the diaphragm into the suction chamber, means for forcing air into the suction chamber and 90 thence through the diaphragm, and a hand operated spring actuated sliding valve, having a transverse passage therethrough for applying the suction means, and a similar transverse passage therethrough for applying the blowing means.

CHARLES E. SMITH.
